UNITED STATES PATENT OFFICE.

HERBERT WHITTER NICHOLES AND JOHN REECE JONES, OF ATLANTA, GEORGIA, ASSIGNORS
TO VENDING SHOWCASE COMPANY, OF ROME, GEORGIA.

COIN-CONTROLLED MECHANISM.

No. 896,235.

Specification of Letters Patent.

Patented Aug. 18, 1908.

Application filed January 3, 1908. Serial No. 409,138.

To all whom it may concern:

Be it known that we, HERBERT WHITTER NICHOLES and JOHN REECE JONES, citizens of the United States, residing at Atlanta, in 5 the county of Fulton and State of Georgia, have invented a new and useful Coin-Controlled Mechanism, of which the following is a specification.

This invention relates to coin controlled 10 mechanism for vending machines, and more especially to machines of that class employed for the sale of cigars and other small objects.

The principal object of the invention is to provide a coin controlled mechanism of very 15 simple construction, for the purpose of unlocking or releasing a selecting and delivering device by which the articles are discharged from the machine.

A further object of the invention is to provide 20 a mechanism of this class in which the deposited coin serves as a fixed cam to coact with a movable cam in effecting the movement of the parts to released position.

With these and other objects, in view, the 25 invention comprises the various novel features of construction and combination of parts, which will be hereinafter more fully described, and pointed out particularly in the appended claims.

30 In the accompanying drawings:—Figure 1 is a sectional elevation of a vending machine provided with coin controlled mechanism constructed in accordance with the invention. Fig. 2 is a sectional plan view of the 35 machine. Fig. 3 is a detail perspective view showing the selecting tongs and the tong support. Fig. 4 is a vertical section through the coin slot. Fig. 5 is a sectional plan view illustrating a slight modification of the invention, the machine being provided with two 40 sets of selecting tongs, one of which is released and allowed to operate on the insertion of a nickel, while the other may be unlocked on the insertion of a quarter dollar and then allowed to operate six times, so that 45 six cigars or other articles may be purchased at one time. Fig. 6 is a detail view of a portion of the mechanism for locking the second set of tongs. Fig. 7 is a detail view of the 50 locking wheel detached. Fig. 8 is a vertical section through the slot in which the quarter dollar is placed.

Corresponding parts in the several figures are indicated throughout by similar characters of reference.

The working parts of the machine are arranged within a suitable casing 10 that is formed principally of glass panels in order that the operation of the parts may be at all times in view.

55 Mounted in suitable bearings in the casing is a shaft 11 carrying a "Ferris" wheel 12 which supports a number of cigar boxes or other receptacles 14. The "Ferris" wheel may be turned in any suitable manner in 60 order to bring any one of the boxes to a selecting position at the front of the casing.

65 Extending across the front of the casing is a horizontally disposed slot 25 in which is arranged a horizontal guide rod 26, and depending from the guide rod is a flat plate 27 that

70 extends down parallel with the inner wall of the casing and preferably is held in contact therewith by a small strip spring 28, although this will not be required where the machine

75 is so supported or locked as to prevent tilting. The upper end of the plate 27 is provided with a pair of spaced outwardly turned lugs having openings for the passage of the rod 26, and between these lugs is arranged a collar 32 that is pivoted on the rod and carries a

80 small sleeve 33 of link-like form in cross section. Through the sleeve 33 slides a pair of tongs 34 that preferably are formed of flat spring wire, the strip of which the tongs are 85 made being preferably bent to form a handle

35 that is located outside the box or casing and is to be grasped and manipulated by the 90 intending purchaser. The inner ends of the tongs are turned downward, forming jaws 36 which normally are held in open position

95 by the inherent elasticity of the wire. The tongs are slidably mounted in the sleeve 33 and may be readily moved to and fro on the rod 26, while the pivotal connection of the sleeve with the rod will permit swinging

movement of the tongs in a vertical plane, so that the tongs may be readily manipulated in the examination and selection of cigars or other articles in the boxes 14. The plate 27 100 is normally held from movement to the left by a stop 40 projecting from the inner face of the front of the casing, and to release the plate and thereby permit the purchaser to

move the tongs to selecting position, it becomes necessary to deposit a coin or check. For this purpose, the front of the casing has a slot 41 into which a coin may be inserted, 5 and the coin falls down, turns to a vertical position, and its edge strikes against the inner face of the plate 27 and forces the same outward so that the plate may clear the stop 40. The inner face of the plate is provided with a 10 cam 42 against which the coins strike, and the coin thereupon becomes slightly wedged between this cam and the inner wall of the slot, so that when the purchaser, grasping the tongs 34, pushes the plate 27 to the left, 15 the cam will ride against the projecting edge of the coin and the plate will clear the stop, so that the selecting tongs may be moved over the cigar box. The rear face of the stop 40 is inclined, forming a cam over which the 20 right hand edge of the plate 27 may readily ride when the plate is moved to the right.

When the tongs have been moved over the cigar box, they may be readily manipulated for the purpose of raising the cigars for examination, and when one that suits the purchaser is found, it is raised by the tongs and the latter are moved toward the right together with the plate 27, so that said plate will pass beyond the straight shoulder of the 25 stop 40 and the plate cannot then be returned for another selecting operation until after the insertion of another coin, it being understood that the previously deposited coin falls from the slot as soon as the plate 27 30 in moving to the left has cleared such slot.

Arranged within the main casing is a partition 48 that is disposed between one side of the revolving carrier and the delivery slide or chute 49, which latter terminates in a 40 drawer or trough 50 into which the selected cigar is delivered. When the operator moves the tongs back to the right, the tongs remain over this chute, and when the tongs are released, the cigar falls by gravity to the delivery point. As before stated, it is then impossible to again move the tongs and plate to selecting position until after the deposit of another coin or check.

The machine is preferably so arranged as 50 to permit the purchase of a single cigar on the insertion of a nickel, or for the purchase of six cigars on the insertion of a quarter. In the latter case a second pair of tongs 34' is employed, this set of tongs being mounted 55 on a plate 27'. The plate 27' is provided with a cam 52 which is arranged to engage with the quarter dollar when the latter falls through the slot 53, as shown in Fig. 8. The plate is further provided with an inwardly 60 extending pin 54 that is arranged to enter a slot 55 formed in a wheel or disk 56 that is mounted on a short shaft or arbor 57 carried by the frame of the machine. The disk 56

is provided with a series of teeth or indentations 58 which are arranged to be engaged 65 by a pawl 59 that is carried by the plate 27', and each time the plate 27' is moved for the purpose of selecting a cigar, the pawl will engage with one of the teeth or indentations and will turn the disk to the extent of one-sixth of a revolution. After six complete movements and the selecting and removal of six cigars, the disk will have been moved through a complete revolution and the pin 54 may reenter the slot 55, thus locking the 70 plate 27 and preventing further movement of the tongs until after the insertion of another quarter dollar.

We claim:—

1. In coin controlled mechanism, a pivotally and slidably mounted plate a tiltable sleeve carried thereby a pair of selecting tongs slidably mounted in said sleeve, a stop disposed in the path of movement of the plate, and a coin engaged cam arranged on 85 said plate, said cam serving by contact with the edge of an inserted coin to swing the edge of the plate beyond the stop.

2. In coin controlled mechanism, a pivotally and slidably mounted plate a tiltable 90 sleeve carried thereby a pair of selecting tongs slidably mounted in said sleeve, a casing having a coin chute arranged to direct the edge of a coin into engagement with the plate, a stop normally limiting the movement of 95 the plate in one direction, and a coin engaging cam carried by the plate and serving during the sliding movement of the plate to swing the latter outward clear of the stop.

3. In a machine of the class described, a 100 horizontally slotted casing, a horizontal rod arranged within the slot, a plate having forwardly bent pivot lugs provided with openings for the passage of the rod, a tiltable sleeve also mounted on the rod and movable 105 with the plate a pair of selecting tongs slidably mounted in said sleeve, the casing having a coin chute through which the edge of the coin may be directed against the plate, a fixed stop for limiting movement of the plate 110 in one direction, and a coin engaging cam carried by the plate and serving during the sliding movement thereof to swing said plate outward clear of the stop.

4. In combination, a pivotally and slidably mounted plate, a selecting device carried thereby, a cam projecting from the plate and arranged to engage an inserted coin, a pin or lug projecting from the plate, a revolute locking disk slotted for the reception of 115 said pin or lug, and means for rotating said disk and moving the slot out of alinement with the pin.

5. In mechanism of the class described, a 120 plate mounted for pivotal and longitudinal movement, a locking pin projecting from the

plate, a revolute disk having a slot for the reception of the pin, interengaging means on the plate and disk for effecting revolute movement of the latter, and a cam projecting from the plate and arranged to be engaged by an inserted coin.

5 In testimony that we claim the foregoing

as our own, we have hereto affixed our signatures in the presence of two witnesses.

HERBERT WHITTER NICHOLAS.

JOHN REECE JONES.
